(57) CLAIM

The ornamental design for a toy lobster, as shown and described.

DESCRIPTION

FIG. 1 is a front, top perspective view of a toy lobster, showing my new design;

FIG. 2 is a rear, bottom perspective view thereof;

FIG. 3 is a rear, bottom perspective view of the toy lobster in another angle;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of detail 10 in FIG. 9.

The dashed broken lines in the figures are for the purposes of illustrating portions of the toy lobster that form no part of the claimed design.

The dashed broken lines immediately adjacent to the bottom edge area in the FIG. 2, FIG. 3 and FIG. 9 are for the purposes of illustrating the boundaries of the toy lobster that form no part of the claimed design, and the portions of the design within the dashed broken lines boundary form no part of the claimed design.

The dash-dot-dash broken lines are for notating enlarged views and form no part of the claimed design.
